(57) **CLAIM**

The ornamental design for a LED camping lantern, as shown and described.

DESCRIPTION

FIG. 1 is a front, right, and top perspective view of a LED camping lantern, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a front, right, and top perspective view of a LED camping lantern, wherein a handle is standing up.

The broken lines shown in the drawings are included for the purpose of illustrating portions of the LED camping lantern that form no part of the claimed design.

1 Claim, 8 Drawing Sheets
